BARRICADE STRUCTURE AND FITTING THEREFOR

Algy E. Martin, North Hollywood, and Mearl D. Lorimer, Los Angeles, Calif., assignors to Light Products, Inc., Beverly Hills, Calif., a corporation of California

Application August 30, 1954, Serial No. 453,082

4 Claims. (Cl. 116—63)

This invention relates to a barricade structure and fitting therefor, and has particular reference to such a structure as may be readily disassembled and moved by authorized personnel, but which may not be disassembled by unauthorized personnel.

It is an object of this invention to provide a simple, sturdy barricade structure which may be readily assembled principally from parts obtainable anywhere in the country.

It is another object of this invention to provide a barricade and sign structure which may be readily disassembled for shipment and storage, which may be readily assembled for use, and which may be locked in assembled position by a simple lock mechanism that precludes disassembly of the sign by anyone who does not have a key to the lock.

It is another object of this invention to provide a barricade structure having means especially adapted to receive a warning light.

It is another object of this invention to provide a barricade structure and warning light in which the warning light is locked to the barricade structure.

It is a further object of this invention to provide a barricade and warning light structure as above, wherein the lock which serves to secure the warning light to the barricade structure also serves to preclude unauthorized disassembly of the barricade structure.

It is a further object of this invention to provide a joint for a barricade structure especially adapted to receive and hold the other members of the sign structure, which other members may be standard parts readily available anywhere in the country.

It is a further object of this invention to provide a joint as above described which is also adapted to receive a fixture box for holding a flashing light.

It is a still further object of this invention to provide a joint as above described which is especially adapted to accommodate a lock that serves to prevent unauthorized removal of the light fixture and/or disassembly of the barricade sign structure.

In accordance with these and other objects which will become apparent hereinafter, preferred embodiments of the present invention will now be described with reference to the accompanying drawings wherein:

Fig. 1 is a perspective view showing the principal elements of the barricade standard and sign structure of the present invention.

Fig. 2 is an exploded perspective view showing the joint and fixture box portion of the barricade standard structure illustrated in Fig. 1.

Fig. 3 is a fragmentary section taken on line 3—3 of Fig. 1.

Fig. 4 is a fragmentary section taken on line 4—4 of Fig. 1.

Fig. 5 is a fragmentary section taken on line 5—5 of Fig. 1.

Fig. 6 is a section taken on line 6—6 of Fig. 5.

2

Fig. 7 is a perspective view showing another embodiment of the present invention.

Referring to the drawings, the barricade is shown consisting of a standard 10, supporting a sign frame 11 comprised of a pair of substantially identical vertical side members 12 (only one of which is shown in the figure), a lower horizontal frame member 13 and an upper horizontal frame member 14. The members 12, 13 and 14 may be any suitable form of shafting, such as conventional water pipe which is readily obtainable anywhere in the country. At its upper end, each vertical member or shaft 12 is secured to the respective ends of the upper shaft or pipe 14 by a conventional pipe elbow 16 into which the pipes 14 and 12 are threaded. If desired, the joint at 16 may be prefabricated by being welded. Within the space outlined by frame 11 is secured a flat sign 17, which may be made of sheet metal or other suitable sheet-like material. The sign 17 has a pair of tubular sleeves 18 formed at each side thereof, which encircle the respective vertical shafts 12 to secure the sign 17 in place in the frame 11.

At their respective lower ends, the vertical shafts 12 are secured to the respective ends of the lower horizontal shaft 13 by a special joint 19 constituting an important feature of the present invention. As seen in detail in Fig. 2, the joint 19 comprises a body having three angularly spaced socket portions 21, 22, and 23, the axes of which are disposed generally co-planar in a vertical plane. Substantially at the common intersection of these three socket axes is the axis of another socket, i. e., a horizontal socket 24. The socket 21 extends directly upward and receives the vertical shaft 12 constituting a portion of the frame 11. The socket 24 is at right angles to the socket 21 and receives the horizontal shaft 13 of the frame 11. Thus the socket 19 serves (among other functions) the purpose of forming one of the corner joints of the frame 11.

The sockets 22 and 23 are directed generally downward but diverge symmetrically away from the vertical axis of the upper socket 21, so as to receive shaft members 26 and 27, respectively, constituting two of the legs of the standard supporting sign frame 11. It will be understood that the other end of the sign frame 11 is similarly equipped with a socket 19 and with legs 26 and 27. At their bottom ends, the legs 26 and 27 are provided with horizontal extensions 28, which serve to give the barricade greater stability particularly against high winds blowing against the face of the sign 17, which tend to tip the barricade over.

Directly opposite the socket 24, the joint 19 is provided with a substantially flat, vertical face 29. In the face 29 are three substantially horizontal tapped or threaded bores 31, 32 and 33 communicating with the interiors of the respective sockets 21, 22 and 23. Threaded in the bore 31 is a set screw 34 which secures the shaft or pipe 12 in the socket 21. To this end, the pipe 12 is provided with an aperture 36 through which the set screw 34 passes, the inner end of the set screw 34 abutting against the inside opposite wall of the pipe 12, which is not apertured. In order to permit the set screw 34 to be recessed in the face 29, the set screw 34 has a socket type head as illustrated at 37.

The legs 26 and 27 are similarly held in place in their respective sockets 22 and 23 by similar set screws 36 threadedly secured in the respective bores 32 and 33, as shown in Fig. 5. Likewise, the horizontal pipe 13 is secured in its socket 24 by a set screw 39 threaded in a tapped bore 41 formed in the upper wall of the socket 24.

In order to maintain the legs 26 and 27 in proper position during assembling of the barricade so as to prevent these legs from blocking full entrance of the shaft 13,

stop bosses 42 are formed on the inside of the joint 19, as shown in Figs. 5 and 6, against which the legs 26 and 27 abut, and are thus limited in their inward mounting in their respective sockets.

The flat face 29 of the joint 19 also has a fourth threaded bore 43 generally centrally located therein and communicating with the interior of the joint 19. Disposed flush against the face 29 is a generally rectangular lamp-receiving fixture box 44, one side 46 of which rests flush against the flat face 29. The box 44 is secured to the joint 19 by means of a bolt 47 (Fig. 4) which passes through an aperture 48 (Fig. 2) formed in the side 46 and is threaded into the tapped bore 43 of the joint 19. The side 46 is also provided with three apertures 49 which register respectively with the three tapped bores 31, 32 and 33, in order to give access to the set screws 34 and 38, after the box 44 has been secured in place.

Extending symmetrically from each side of the face 29, the joint 19 has a pair of ears, 51 and 52 provided with apertures 53 and 54 respectively. As will be seen in Fig. 2, the opening 48 in the side 46 of the box 44, with its associated openings 49 is not centrally located in the side 46; therefore the box 44 extends asymmetrically out from the joint 19.

In that portion of the side 46 extending asymmetrically out from the joint 19, there is provided an aperture or opening 56 which registers with the aperture 54 in the ear 52. A warning lamp 57 is disposed in the box 44 and is provided with a reinforced nut 58 (Fig. 3) welded thereto which receives a securing bolt 59 therein passed through the ear 52 and the side 46 as seen in Fig. 3. The bolt 59 serves to prevent removal of the lamp 57 from the box 44. In order to prevent unauthorized loosening and removal of the bolt 59, the head 61 of the bolt 59 is covered by a locked cover 62, which is held in place by a lock controlled finger 63 engaging in a slot in a specially formed washer 64 placed under the head 61. In this way, the bolt 59 may not be unscrewed except by one having access to the locked cover 62 by means of a key 66.

In order to further fortify the box 44 against unauthorized removal of the lamp 57, the open top of the box is provided with inwardly extending flanges 67 which overlie the housing portion of the lamp 57 but which still permits the upward protrusion of the dome portion 68 of the lamp. One end of the box 44 is open but the other is closed by a strap 69 welded thereacross between the side walls of the box.

Loosening of the bolt 59 by rotation of the locked cover 62 is prevented by the sockets 21 and 22 of the fitting 19.

From the above description it will be seen that the joint 19 serves the multiple purpose of securing together the lower portions of the frame 11; of receiving the barricade legs 26 and 27; and of supporting the fixture box 44. It will also be seen that the joint 19 constitutes a medium by means of which the barricade may be held in assembled position against unauthorized disassembly, and by means of which the box 44 and warning lamp 57 may be secured to the barricade against unauthorized removal—all with a single locking member 62. When the locked cover 62 is removed, not only is access provided to remove the lamp 57, but such removal of the lamp 57 also gives access to the securing bolt 47, by means of which the box 44 may be removed if desired, and to the set screws 34 and 38, which permit disassembly of the barricade structure for easier transportation and storage. It will be further noted that it is not necessary to remove the box 44 in order to remove the set screws 34 and 38, since they may be taken out through the apertures 49, even with the box 44 in place.

It will be further noted, particularly by reference to Fig. 4, that the presence of the sheet metal sign 17 blocks access to the set screw 39, so that the horizontal shaft 13 may not be removed without authorization. The sign 17 is taken out of the way simply by removing the set

screws 34 and lifting the vertical shafts 12 from their respective sockets 21.

The configuration of the fitting 19 makes it possible to easily bolt a line of barricades together to form a long structure that may extend continuously across a road. This is done by removing the box 44, through removal of the bolt 47; and butting the face 29 of one barricade against the face 29 of an aligned barricade. Securing bolts may then be passed through one or both of the holes 53 and 54 and secured in place by nuts. Locks may be provided for these bolts and nuts if desired.

It will therefore be readily apparent that there has been provided a simple barricade structure, the key to which is a readily cast joint, so constructed that a single lock member serves to prevent the slightest unauthorized disassembly of the barricade, yet which, when properly authorized, one may completely knock down to its elemental components for ready transportation and storage.

The fixture box 44 is not limited in its use to a barricade structure of the type illustrated in Fig. 1, but may be welded atop a single upright vertical member 73, as shown in Fig. 7. The upright 73 is supported by a standard (not shown), and serves to hold in visible position a flashing light 57 which is locked in place by a locked bolt cover 62 as illustrated before. While the same style box as shown in Fig. 2 may be employed for this purpose, it is preferred to omit the holes 48 and 49, and to provide the side 46 with protrusions or dimples 74, which bracket the lock cover 62 and prevent rotation thereof, thereby guarding against unauthorized loosening of the securing bolt 59.

While the instant invention has been shown and described herein in what is conceived to be the most practical and preferred embodiment, it is recognized that departures may be made therefrom within the scope of the invention which is therefore not to be limited to the details disclosed herein but is to be accorded the full scope of the claims.

What is claimed is:

1. Combined standard and fixture box comprising: a joint having three angularly spaced sockets therein adapted to receive shaft members therein, said sockets having intersecting axes disposed in a substantially vertical plane, said joint also having a fourth socket extending horizontally from said vertical plane and adapted also to receive a shaft member; said joint having a substantially flat vertical face opposite said fourth socket, said face having three substantially horizontal threaded bores communicating with the respective three sockets; each of said sockets having a shaft member secured therein; a plurality of set screws one in each of said threaded bores and securing said shaft members in said sockets; said joint having a pair of apertured ears extending outwardly from each side of said face; a fixture box having one side thereof abutting said joint face, said box side having openings aligned with the threaded bores in said joint to give access to said set screws; said box side having an aperture registering with the aperture in one of said ears, thereby to receive a bolt for securing a fixture within said box, the head of said bolt being opposite side joint face, said face having a fourth threaded bore generally centrally located therein and said box side having a generally centrally located opening therein registering with said last named bore in said face for receiving a screw for holding said box to said joint.

2. Barricade structure comprising: a sign frame including a lower horizontal member, a pair of vertical side members and an upper horizontal member, two pairs of supporting legs located at the respective ends of said frame, each leg extending downward from a lower corner of the sign frame; said corner being occupied by a joint having three angularly spaced sockets therein, two of said sockets being directed generally downward and receiving the two legs of a given pair, the third socket being directed upwardly, vertical side members of said

frame being received in the upwardly directed sockets, said joint also having a fourth socket directed generally horizontally and receiving the lower member of said frame, said joint having a vertical face opposite said fourth socket which is substantially flat and having therein three threaded bores communicating respectively with the first three mentioned sockets in said joint, each of said bores having a set screw therein securing the respective legs and members in said joints, each said joint also having at least one apertured ear extending outwardly from one side of said face, a fixture box having one side thereof abutting said joint face, said box side having openings therethrough aligned with the threaded bores in said joint to give access to said set screws, said box side having an aperture registering with the aperture in said ear, thereby to receive a fixture securing bolt, said face having a fourth threaded bore generally centrally located therein, said box having a generally centrally located opening therein registering with said fourth bore in said joint face, a screw passing through said last mentioned opening and threaded into said fourth bore for holding said box firmly against said joint, a flashing light disposed within said box, a bolt passing through said ear aperture and through the registering opening in said box and

threaded into said flashing light to secure the same to said box, and a locked cover secured over the head of said bolt to prevent unauthorized unscrewing thereof.

5 3. Box for receiving a flashing lamp having an upwardly projecting dome, comprising: a bottom and side walls, each said side wall having an inwardly extending flange, said lamp being adapted to reside within said box with said dome projecting upwardly between said flanges, means comprising a strap wall across one end of the 10 box for securing said side walls against forceable separation, and means forming an opening in one of said walls for passing a bolt for securing said lamp in the box.

10 4. Box according to claim 3 having outward protrusions adjacent said opening adapted to prevent rotation 15 of a lock cover secured over the bolt head.
